S. M. Hino

UNITED STATES PATENT OFFICE.

SETH M. HINO, OF ROCK SPRINGS, WYOMING.

ELECTRIC LAMP.

1,120,492.

Specification of Letters Patent.

Patented Dec. 8, 1914.

Application filed November 12, 1912. Serial No. 730,933.

To all whom it may concern:

Be it known that I, SETH M. HINO, a citizen of the United States, residing at Rock Springs, in the county of Sweetwater and State of Wyoming, have invented new and useful Improvements in Electric Lamps, of which the following is a specification.

This invention relates to improvements in electric lamps and has particular application to variable candle power incandescent lamps.

In carrying out the present invention, it is my purpose to provide an incandescent lamp wherein by means of a plurality of independent filaments the candle power of the lamp may be varied.

It is also my purpose to provide an incandescent lamp wherein by means of a plurality of independent filaments and switches controlling the flow of current to the filaments, the latter may be rendered incandescent to give the desired candle power and which will embrace the desired features of simplicity, efficiency and durability coupled with cheapness of cost in manufacture and marketing, and furthermore, my improved lamp may be applied to any type of socket and removed therefrom when desired.

With the above and other objects in view, the invention consists in the construction, combination and arrangement of parts hereinafter set forth in and falling within the scope of the claim.

In the accompanying drawings, Figure 1 is a view in elevation of a lamp constructed in accordance with my present invention, the bulb being partly broken away. Fig. 2 is a fragmentary sectional view through the lamp.

Referring now to the accompanying drawings in detail, the numeral 1 indicates the threaded plug of the lamp which is preferably of hollow construction and lined internally with suitable insulating material 2, the plug 1 being adapted to fit any type of lamp socket as will be readily understood. Depending from the plug 1 and in open communication therewith is a hood 3 insulated from the plug by a ring 4 of insulating material and composed of annular metallic sections 5, 6 and 7 of various diameters and insulated from one another as at 8.

The numeral 8' indicates the lamp bulb which is constructed as usual and has the relatively small end thereof secured within the

lower section 7 of the hood 3, while depending into the bulb and formed integral with the upper end thereof is the protecting tube 9, the latter having formed integral with the free end thereof a glass rod 10. This rod 10 is provided with sets of radially extending fingers 11 suitably spaced apart along the length of the rod and forming with the rod a filament support. The section 5 of the hood 3 is formed with a series of apertures suitably spaced apart and carrying insulating washers 12 into each of which is threaded a pivot pin 13 terminating in a bifurcated head 14 and pivoted within such head between the bifurcations thereof is one extremity of a switch blade 15 provided with a manipulating handle 16 constructed of suitable insulating material and having the free end thereof adapted to engage the bifurcated end of a contact 17 carried by the section 6 of the hood in alinement with the pivot post of the respective blade.

Upon the head of the plug 1 is a contact 18 from which leads a conductor 19 extending through the tube 9 by way of the plug 1 and hood 3. A second contact 20 is secured to the side of the plug 1 and from the last-named conductor leads a conductor 21 terminating in branch wires 22 each of which leads and is electrically connected to the pivot stud of one of the switch blades. From the contacts 17 of the switch blades lead conductors 23, 24 and 25 which extend through the tube 9 and are insulated from one another and from the conductor 19 by suitable packing material. Connected to the free terminal of the conductor 23 is one end of a filament 26 extending approximately the full length of the rod 10 and supported by the outer sets of radial fingers 11 and having the free terminal thereof tapped onto the conductor 19, while to the free terminal of the conductor 24 is fastened one end of a second filament 27 of less length than the filament 26 carried by the sets of fingers 11 inwardly of and adjacent to the outer sets of such fingers, the free terminal of the last-named filament being also connected to the conductor 19. A third filament 28 has one terminal thereof tapped onto the free-end of the conductor 25 and is carried by the innermost sets of fingers 11 and has the free end thereof connected to the conductor 19.

From this construction, it will be seen that the filaments of the lamp are connected

in multiple or parallel with the contacts 18 and 20 and may be rendered incandescent independently of one another through the medium of the switches composed of the 5 blades and contacts. For instance, should it be desired to render the filament 26 incandescent, the switch in the conductor 23 is closed whereby current flows through the said filament and illuminates the lamp to 10 the desired candle power. Should it be desired to lessen the candle power of the lamp, the switch in the conductor 23 is opened and one of the other switches closed whereby a 15 smaller length of filament will be rendered incandescent to illuminate the lamp. On the other hand, should it be desired to obtain the full candle power from the lamp all of the switches are closed thereby enabling the current to travel through all of the 20 filaments and illuminate the lamp to its greatest capacity. Although I have shown the three filaments and a similar number of switches for controlling the same, it will be

apparent that any number of filaments and switches may be employed.

25

I claim:

In an electric lamp, a rod, sets of radially extending fingers secured to said rod and suitably spaced apart along the length thereof and having the outer ends thereof 30 bent upon themselves to form eyes, filaments carried by the respective sets of fingers and disposed one within the other and of relatively different lengths, each filament being trained through the eyes of the 35 respective fingers, an electric circuit including said filaments in multiple, and means whereby said filaments may be illuminated independently of one another.

In testimony whereof I affix my signature 40 in presence of two witnesses.

SETH M. HINO.
